STARTING DEVICE FOR GAS ENGINES

Original Filed June 3, 1921

UNITED STATES PATENT OFFICE.

JOHN V. RICE, JR., OF BORDENTOWN, NEW JERSEY, ASSIGNOR, BY MESNE ASSIGNMENTS, TO FRED E. TASKER, OF NEW YORK, N. Y.

STARTING DEVICE FOR GAS ENGINES.

Application filed June 3, 1921, Serial No. 474,778. Renewed May 24, 1927.

My present invention relates to a starting device for internal combustion engines, and to the special class of starters known as pneumatic starters, in which air pressure is introduced into the engine so as to act against the piston and impart an initial impulse thereto.

In the accompanying drawing illustrating my invention:

10 The single figure shown is a vertical section of a portion of the cylinder of a gas engine with my improved starting device applied thereto, a fragment of the piston being indicated in side elevation.

15 My invention is primarily adapted for use with the engine shown and described in my Letters Patent No. 1,429,254 dated Sept. 19, 1922, for internal combustion engine, wherein in a two-cycle engine is fully set forth, but 20 it will be obvious that I am not restricted to this kind of engine and that the invention has a wide application to all kinds of explosion and other engines wherein it is desired to introduce air pressure to initially move a 25 reciprocating member.

In the particular specimen of mechanism shown in this case, for explanatory purposes merely, I have selected the type of two-cycle engine set forth in the aforesaid Letters Patent, wherein 1 denotes a cylinder having an explosion chamber A, a compression chamber E in the end of the cylinder, and a part of the piston 4.

30 In the side wall of the cylinder frame is an inlet passage 31 for the incoming explosive mixture or fuel which flows from the passage 31 through the ports 32 in the cylinder wall and enters the chamber E, whence it passes through the piston 4 to the other compression chamber (not shown) and makes its way throughout the different ports and 35 passages in a manner fully explained in said Letters Patent.

40 In an engine of this character, I introduce air pressure into the explosion chamber at the proper time so that it may act against the piston, at 4° for example, and cause it to move downward in the direction shown by the arrow. The wall of the cylinder 1 is provided with a suitable opening entered by 45 screw-threaded passage 105, into which is screwed the valve casing 107. Said casing 107 has in the side thereof an opening 113 50 into the passage 114, which communicates with the passage 106 leading to some suitable

storage of air which may be in a reservoir supplied by an automatic pump actuated by the movement of the engine (not shown). Passage 106 with its lateral outlet 114 is preferably fastened to the casing 107 by a 60 screw device 112. In connection with the end of the casing 107 and opening into chamber A is an air inlet valve 117 having a beveled edge which rests on a beveled seat so that when the explosion takes place in chamber A this valve 117 will merely be pressed firmly to its seat and will be capable of 65 withstanding the effects of the explosion. Valve 117 has a stem 115 which passes through the casing 107 and is made integral with or 70 securely fastened to another stem 103 which projects from the opposite end of the valve casing and is properly packed by means of a gland 109, a screw cap 108 which screws into the end of the valve casing, and an inner nut 75 116 which serves to make a tight joint. On the stem 103 inside the casing 107 is a screw-threaded section 111 on which is a traveling 80 adjustable nut 110 between which and the opposite end of the valve casing is ranged a 85 spring 113 which acts to draw the valve 117 back upon its seat after it has been unseated to open it and allow starting pressure to enter the chamber A.

A shaft 100 runs alongside of the cylinder 85 and is supported in a bracket 104, arranged in some suitable way above the main supporting frame 15 and having thereon cams 101 which are adapted to engage the end of the projecting valve stem 103. When a cam 90 acts against the end of stem 103 the said stem will be depressed and the valve 117 opened so that air will rush through the passage 106 into the passage 114 and opening 113 into the valve casing, and out past the valve 117 into the chamber A where it will 95 act against the piston at 4° and start the same in a rectilinear movement, or will reverse the operation, driving the crank-shaft in one direction or the other.

Having thus described my invention, what I claim as new and desire to secure by Letters Patent, is:

In a device of the class described, the combination with a piston and a chamber surrounding the same, of a valve device on the wall of said chamber comprising a valve casing, having a lateral air inlet, a pipe for carrying air pressure into said casing, a valve opening from the casing into the chamber, 105 a valve opening from the casing into the chamber, 110

ber, said valve having a threaded stem, an open spring whose coils are loose and wide apart so that air may pass freely through them, an adjustable nut on the threaded part of the stem between which and the opposite end of the valve casing the spring is arranged, a second stem aligned with and connected to the other stem and projecting

from the valve casing, a packing gland therefor, a screw cap for the valve casing, a shaft and a cam thereon to engage the outer end of the stem, and move it to open the air inlet valve.

In testimony whereof I hereunto affix my signature.

JOHN V. RICE, JR.
